UNITED STATES PATENT OFFICE.

WILLIAM P. DE SAUSSURE, JR., OF ENGLEWOOD, NEW JERSEY.

VISIBLE INDEX.

Application filed January 15, 1924. Serial No. 686,287.

This invention relates to visible indexes or information racks, and aims to improve the operation of devices heretofore used for this purpose and to adapt them to additional uses.

The invention relates to the type of visible index in which a series of card holders are stacked in a rack. Visible indexes of this type are shown in Patent No. 1,103,344, 10 issued to George S. Tiffany and me on August 4, 1914, and in my application filed August 31, 1921, Serial No. 497,154, Patent No. 1,483,215, dated February 12, 1924.

An object of the present invention is to prevent displacement or mixing of the card holders when they are moved apart for inserting other cards in the holders. A further object is to space the card holders apart from one another in order to make provision 20 for a plurality of cards in each holder, or for the insertion of signal devices between the holders. Another object is to provide for holding certain cards permanently in the holders and permitting the temporary 25 insertion of other cards. A still further object is to provide the holders with sliding signal devices, and so to relate the card holding means with the signal device of each holder as to insure the display of a 30 predetermined signal when a card is removed from the holder.

A visible index embodying the present invention is of particular value when used for a room index for hotels, and when so used 35 serves to indicate when each room is made up and unsold, made up and sold, occupied, or not made up and unsold. The index thus serves to tell the room clerk the exact condition of each room at any time. Many 40 features of the invention are, however, useful in connection with indexes used for other purposes.

The invention may best be understood by a detailed description of the specific room 45 indexes embodying it which are illustrated in the accompanying drawings, in which:

Fig. 1 is a front elevation of a room index embodying the invention in the form which I consider most desirable;

Fig. 2 is a side elevation of an index 50 shown in Fig. 1 sectioned on the line 2-2 of Fig. 3;

Fig. 3 is an enlarged horizontal section 55 of the index taken on the lines 3-3 of Figs. 1 and 2;

Fig. 4 is a view similar to Fig. 3, but on a

smaller scale, showing a modified form of rack frame;

Fig. 5 is a front face view of one of the card holders with its parts in position to indicate that a room is made up and unsold;

Fig. 6 is a front face view of one of the card holders with its parts in position to indicate that a room is made up and sold;

Fig. 7 is a front face view of one of the card holders containing a name card to indicate that a room is occupied;

Fig. 8 is a front face view of one of the card holders with its parts in position to indicate that a room is not made up and unsold;

Fig. 9 is an enlarged transverse section on the line 9-9 of Fig. 5;

Fig. 10 is an enlarged transverse section 75 on the line 10-10 of Fig. 6;

Fig. 11 is an enlarged transverse section on the line 11-11 of Fig. 7;

Fig. 12 is an enlarged longitudinal section 80 on the line 12-12 of Fig. 6;

Fig. 13 is an enlarged longitudinal section on the line 13-13 of Fig. 7;

Fig. 14 is a perspective view of one of the card holders;

Fig. 15 is a perspective view of one of the 85 room number cards;

Fig. 16 is a perspective view of one of the signal cards;

Fig. 17 is a perspective view of one of the 90 signal slides;

Fig. 18 is a perspective view of one of the room data cards;

Fig. 19 is a perspective view of one of the 95 transparent strips;

Fig. 20 is a perspective view of one of the 100 removable guest cards; and

Figs. 21, 22, 23 and 24 are face views similar to Figs. 5, 6, 7 and 8, respectively, showing a modified card holder and the parts associated therewith.

The visible index comprises a rack frame 10 and a plurality of card holders 20 mounted in the rack frame. The rack frame 10, which is most desirably formed of sheet metal, comprises a flat back 11, two parallel 105 sides 12, and two front flanges 14, 15 extending inwardly from the sides. The upper end of the back 11 may be bent forward to provide a top 16 for the rack. A support for the lowermost card holder is provided at the bottom of the rack. This support may consist of an upwardly inclined shelf.

17. For a reason hereinafter explained it is detachably secured to the rack frame by means of a screw 18 entering the back 11.

Each card holder 20 is formed from a piece of sheet metal or other suitable material. Each card holder consists of a plate 21 having at its top a turned-over flange 22 and at its bottom edge a short turned-over flange 23 and a longer flange 24 projecting perpendicularly outward. The card holder is provided with rearward projections 25 and with forward projections 26, 26', all of which are stamped from the plate 21.

When the card holders are placed in superimposed relation in the rack frame 10, as shown in Figs. 1, 2 and 3, the rearward projections 25 of each holder serve to support the lower edge of the next holder above so that the holders are retained in overlapped relation. The forward projections 26, 26' and the flanges 24 of the holder serve to space the holders apart from each other and to keep them parallel to each other. In order to prevent the holders from being relatively displaced, or mixed up, after they have been placed in the rack frame, each holder has at each of its ends a recess 27 which engages a longitudinal projection, or rail, 19 at the inner surface of each side 12 of the rack frame. The projections 19 preferably have the form of removable rods, as shown in Figs. 2 and 3. The rods 19 extend between the bottom shelf 17 and the top 16 of the frame and engage the recesses 27 of each holder. When the bottom piece 17 is removed both the rods and the holders may be removed from the frame. Besides serving to prevent relative displacement of the holders, the rods 19 serve to retain each holder inclined forwardly from the back 11 of the frame.

The longitudinal projections 19 may be restrained against forward or outward movement—as for example by making longitudinal projections 19^a integral with the sides 12 as shown in Fig. 4—and in this case the front flanges 14, 15 at the sides 12 may be omitted as the fixed projections will serve to prevent outward movement of the card holders 20.

In order to adapt the index for use as a room index, each card holder has a number of parts associated with it which, while they are detachably secured to the holder, are not detached from the holder in the ordinary use of the index, and may, therefore, be regarded as permanent parts of a holder. They include a signal card 30, two slides 40, 40', a room number card 50, a transparent strip 60, and a room data card 70.

The signal card 30, Fig. 16, is placed over the front face of the plate 21 of the holder with its upper edge under the flange 22 and its lower edge under the flange 23 and on the

flange 24. It contains a vertical slot 31 which fits over the forward projection 26 of the holder. One end of the card 30 engages the forward projection 26'. The card 30 contains two horizontal slots 32, 32' which lie over corresponding slots 28, 28' in the plate 21. The portions of the front face of the card 30 just to the right of each of the slots 32, 32' are colored in some bright color such as red. The remainder of the card may be colored or not, as desired. I have found, however, that economy in manufacture may be effected by marking or printing a strip of color 33 along the upper portion of the front face of the card 30.

The slide 40, Fig. 17, has a flat body 41 with a rearwardly projecting tab 42 at one end and a forwardly projecting tab 43 at the other end. The slide is placed with its body 41 over a part of the colored strip 33 of the card 30 and with its rear tab 42 in the slot 32 of the card 30 and the slot 28 of the plate 21. The slide 40' is like the slide 40 and is similarly applied with its rear tab 42' in the slots 32', 28'.

The room number card 50 is applied over the body 41 of the slide 40 and over the card 30 with its upper edge under the flange 22 and its lower edge under the flange 23. Its inner side edge abuts against the projection 26.

The transparent strip 60 is applied over the upper portions of the room number card 50 and the signal card 30 and over the bodies 41, 41' of the slides 40, 40'. Its upper edge is held by the flange 22 while its lower edge is held in notches 29 formed in the projections 26, 26'. The transparent strip contains two slots, 62, 62', parallel to and spaced longitudinally to the right from the slots 28, 28' in the plate 21. The forwardly projecting tabs 43, 43' of the slides 40, 40' project through the slots 62, 62', respectively. The slides may be moved longitudinally of the holder by pushing their front tabs 43, 43'. In such movement, the rear tabs 42, 42' of the slides slide in the slots 28, 32, 28', 32', while the front tabs 43, 43' of the slides slide in the slots 62, 62'.

Since the room number card 50 and the transparent strip 60 can be removed from the holder only by endwise movement, the parts thus far described cannot be removed from the holder when it is in the rack frame and may therefore be regarded as parts permanently associated with the card holder.

The room data card 70 is applied over the signal card 30. Its upper portion extends under the transparent strip 60 while its lower edge rests on the flange 24. Its right hand end engages the forward projection 26' while its left hand end 71 lies some distance to the right of the projection 26. The card 70 has a recess 72 in its upper

right hand corner through which a portion of the colored strip 33 of the card 30 may be seen through the portion of the transparent strip 60 adjacent to its slot 62. Another portion of the colored strip 33 may be seen through the portion of the transparent strip 60 adjacent to the slot 62, since this portion of the colored strip lies beyond the left-hand end 71 of the card 70. All the rest of the colored strip 33 is covered either by the room number card 50 or by the room data card 70. The two portions of the colored strip 33 which are not covered by these cards are covered by the bodies 41, 41' of the slides 40, 40' when the slides are pushed to the right. On the card 70 may be marked data as to the room whose number appears on the card 50 of the same holder. Thus the card 70 may carry a description of the size and furnishings of the room. While the card 70 is not removed from the holder in the ordinary use of the index, it can be removed without taking the holder out of the rack frame, and a new room data card may be substituted for it by merely inserting the upper portion of this card under the transparent strip and allowing its lower edge to rest on the perpendicular flange 26. Consequently, when a change is made in the rate or furnishings of any room a new room data card may be inserted in the holder corresponding to this room without disturbing the rest of the index.

In addition to the parts described, which are more or less permanently associated with each card holder, a temporary card or guest card 80, Figs. 7 and 20, may be mounted in each card holder in the use of the index. The temporary card or guest card 80 may bear the name and address of the guest occupying the room whose number appears on the card holder. The guest card 80 may be applied to a holder by inserting its upper portion under the transparent strip 60 between the projections 26 and 26' and allowing the lower edge of the card to rest on the flange 24. It will be noted that the guest card can be inserted in a holder only when the slide 40' is pushed to the left and the slide 40' is pushed to the right, and that, when the guest card is removed from the holder, the slides occupy these positions until moved by means of their front tabs. Instead of inserting the upper portion of the guest card under the transparent strip 60, it may be simply dropped into the pocket formed between each holder and the holder next below.

The use of the index which has been described is as follows:—The card holders are arranged in the frame 10, or in a plurality of such frames, with the numbers of their room number cards 50 in predetermined order. The slides 40 and 40' of each holder are pushed to the left, so that portions of

the colored strips 33 are visible adjacent to the slot 62 and the slot 62' as shown in Fig. 5. The colored signal at the slot 62 indicates that the room is unsold, while the colored signal at the slot 62' indicates that the room is made up. When any room is sold or engaged, the room clerk moves the slide 40 of the corresponding card holder to the right, covering the colored signal adjacent to the slot 62. The card holder then appears as shown in Fig. 6, indicating at a glance that the room is sold and that it is made up. When, on the arrival of the guest, the guest card 80 is made out, the slide 40 is moved to the left, the slide 40' is moved to the right, and the guest card 80 is inserted in the holder. It should be noted that the slides 40 and 40' will block the entrance of the guest card unless moved to the left and right respectively before the card is inserted. After the insertion of the guest card the card holder and the guest card appear as shown in Fig. 7, indicating that the room is occupied and by whom it is occupied. When the guest leaves, the guest card is removed. This leaves the slide 40 at the left and the slide 40' at the right, so that the card holder appears as indicated in Fig. 8. The colored signal adjacent to the slot 62 indicates that the room is unsold, while the absence of a colored signal adjacent to the slot 62' indicates that the room has not been made up and is, therefore, not ready for occupancy by another guest. As soon as the clerk is informed that the room has been made up, he moves the slide 40' to the left. The card holder then again presents the appearance shown in Fig. 5, indicating that the room is ready for another guest.

From the above description it is apparent that the index keeps the room clerk constantly informed as to the exact condition of each room. It also tends to avoid mistakes in the signals because of the fact that the signals are necessarily in proper position when a guest card is removed from any holder.

The guest cards may easily be inserted under the strip 60 and removed by raising any number of the holders in the rack. During such movement of the holders, they are held in proper inclined relation, both by the engagement of their rear tabs with the back 11 and by the engagement of their side recesses with the rods 19.

If for any reason it is wished to call special attention to a particular room, a special signal piece 90 may be inserted in front of the room number card of the card holder for this room. The spacing of the holders by the projections 26, 26' and the flange 24 allows space for the insertion of this signal piece.

In Figs. 21 to 24 I have illustrated a

simplified form of card holder and associated parts which may be manufactured at less cost than the card holder already described, and, while not quite as convenient as the form described, may nevertheless be used to give the room clerk the same information. The holder 20^a shown in Figs. 21 to 24 and the parts associated with it are similar to the holder 20 and the parts associated with it, except that the slide 40' and the slots for the tabs of this slide are omitted. In the use of this holder the colored signal which appears through the portion of the transparent strip 60^a adjacent to its slot 62^a when the slide 33 is pushed to the left may be used, as before, to indicate that the room is unsold. After a guest leaves, the guest card 80 is removed from the holder and may be folded and reinserted in the holder. In reinserting the card it may be placed with its upper portion under the transparent strip 60 or may be simply dropped into the space or pocket between the holder in which it was inserted and the holder next below, so that it stands on the flange 24 as shown in Fig. 24. In either case, the folder card leaves the signal adjacent to the slot 62^a uncovered, thus indicating that the room is unsold, while the presence of the folder guest card in front of the holder indicates to the clerk that the room is not made up. When the clerk receives word that the room has been made up, he removes the folder guest card from the holder, leaving the holder as shown in Fig. 21, indicating that the room is made up and unsold.

What is claimed is:

1. A visible index, comprising a rack frame having parallel sides, a longitudinal projection extending along the inner surface of one of the sides, and a series of card holders slidably mounted in inclined overlapping superposed relation in the rack frame and extending between the sides thereof, the bottom of each holder engaging a part of the frame extending parallel to said longitudinal projection and each holder having in one end a recess of substantially greater width than said projection engaging said projection, whereby the holder is held inclined to the projection and parallel to the other holders.
2. A visible index, comprising a rack frame having parallel sides, longitudinal projections extending along the inner surface of each of the sides, and a series of card holders slidably mounted in inclined overlapping superposed relation in the rack frame and extending between the sides thereof, the bottom of each holder engaging a part of the frame extending parallel to said projections and each holder having in each of its ends a recess of substantially greater width than said projections engag-

ing one of said projections, whereby the holders are retained in their inclined position.

3. A visible index, comprising a rack frame having a back and parallel sides, a longitudinal projection extending along the inner surface of one of said sides, and a series of card holders slidably mounted in inclined overlapping superposed relation in the rack frame and each having a rearward projection adapted to support the lower edge of the holder next above, the bottom of each holder engaging the back of the frame and each holder having a notch of substantially greater width than said longitudinal projection in one of its ends engaging said projection, whereby the holders are retained in their inclined position.

4. A visible index, comprising a rack frame having parallel sides, a rod removably mounted in the rack frame and extending along the inner surface of one of the sides, and a series of card holders slidably mounted in inclined overlapping superposed relation in the rack frame and extending between the sides thereof, and each holder having in one end a notch which engages said rod and is of substantially greater width than the width of the rod, said rod serving in cooperation with a part of the frame to retain the holders in their inclined position.

5. A visible index, comprising a rack frame having parallel sides, two longitudinal rods removably mounted in the rack frame and extending along the inner surface of the two sides respectively, and a series of card holders slidably mounted in inclined overlapping superposed relation in the rack frame and extending between the sides thereof, each holder having in each of its ends a notch which engages one of the rods and is of a width substantially greater than the width of the rod, the rod serving in cooperation with a part of the frame to retain the holders in their inclined position.

6. A visible index, comprising a rack frame having parallel sides, two rods removably mounted in the rack frame and extending along the inner surfaces of the sides respectively, and a series of card holders slidably mounted in inclined overlapping superposed relation in the rack frame and extending between the sides thereof, each card holder having in each of its ends a notch which engages one of the rods and is of a width substantially greater than the width of the rod, the rod serving to retain the holders in the rack frame and in cooperation with a part of the frame to retain the holders in their inclined position, and each card holder having a rearward projection adapted to support the lower edge of the holder next above it.

7. A visible index, comprising a rack frame, and a series of card holders slidably mounted therein, each card holder having a rearward projection spaced from its lower edge and supporting the lower edge of the holder next above, and forward projections engaging the back of the holder next below so as to retain the holders spaced apart from each other.
8. A visible index, comprising a rack frame, and a series of card holders mounted therein, each card holder having a rearward projection spaced from its lower edge of the holder and supporting the lower edge of the holder next above, a flange extending forwardly from its lower edge and engaging the back of the holder next below, and a forward projection of the same height as said flange engaging the back of the holder next below.
9. A visible index, comprising a rack frame, and a series of card holders slidably mounted therein, each card holder having a rearward projection spaced from its lower edge and supporting the lower edge of the holder next above, and a plurality of forward projections, all said forward projections being located further from the upper edge of the holder than the distance between the lower edge of the holder and its rearward projection.
10. In a visible index, a card holder comprising a plate having an overturned edge along its top, two forward projections on said holder, and a transparent strip held between the turned-over edge and the upper edges of said projections.
11. In a visible index, a card holder comprising a plate having a turned-over flange along its upper edge and a perpendicular flange at its lower edge, forward projections on said holder between said flanges, a transparent strip retained between the turned-over flange and said projections, and a card temporarily retained in said holder with its upper portion inserted under said strip between the projections and its lower edge resting on said lower flange.
12. In a visible index, the combination of a card holder, a signal device slidably mounted on said card holder, and means whereby a card temporarily mounted in said card holder will prevent sliding of the signal device.
13. In a visible index, a card holder comprising a plate containing a slot, a strip secured over said plate and containing a slot parallel to the slot in the plate, and a slideable signal device having a body between the plate and the strip, a rearward projection entering the slot in the plate, and a forward projection entering the slot in the strip.
14. A visible index, comprising a rack frame and a series of card holders as claimed in claim 13 slidably mounted in said rack,
15. In a visible index, a card holder comprising a plate containing a slot, a transparent strip mounted over the upper portion of the front face of the plate and containing a slot parallel to the slot in the plate, and a slide having a body located between the plate and the strip, and a rearward projection entering the slot in the plate, and a forward projection entering the slot in the strip, the holder being adapted to hold a card temporarily with its upper portion extending under the portion of the strip containing the slot to prevent movement of the slide.
16. In a visible index, a card holder comprising a plate containing a slot, a transparent strip mounted over the upper portion of the front face of the plate and containing a slot parallel to the slot in the plate, and a slide having a body located between the plate and the strip and a rearward projection entering the slot in the plate and a forward projection entering the slot in the strip, the holder being adapted to support a card temporarily in position to prevent movement of the slide.
17. In a visible index, a card holder comprising a plate containing a slot, a color card mounted against the front face of the plate and containing a slot registering with the slot in the plate, a transparent strip mounted over the upper portion of the front face of the colored card and containing a slot parallel to the slot in the plate, a card mounted on the card holder with its upper portion extending under said transparent strip and covering all of said colored card except the portion visible through a portion of the strip adjacent to the slot therein, and a slide having a body located between the colored card and the strip and a rearward projection entering the slot in the plate and the slot in the colored card and a forward projection entering the slot in the strip, the holder being adapted to support a card temporarily in position to prevent movement of the slide.
18. In a visible index, the combination of a card holder, two signal devices slidably mounted on the card holder for movement toward and away from each other, and means for temporarily mounting a card in said card holder between said signal devices to prevent sliding either of them toward the other.
19. In a visible index, a card holder comprising a plate having an overturned flange along its upper edge, an overturned flange extending along a portion of its lower edge, and a perpendicular flange extending along the remainder of its lower edge, spaced for

ward projections on the plate between its upper and lower edges, a card permanently attached to the holder and having its upper and lower edges held by said overturned flanges, a strip permanently attached to the holder and having its upper edge held by the upper overturned flange and its lower edge held by said projections, and a card temporarily attached to the holder with its upper portion inserted under the strip and **10** its lower edge resting on the perpendicular flange.

In testimony whereof I have hereunto set my hand.

WILLIAM P. DE SAUSSURE, JR.
